UNITED STATES PATENT OFFICE

104,197

DESIGN FOR A RADIO RECEIVER CABINET

John R. Morgan, Oak Park, Ill., assignor to Sears, Roebuck and Co., Chicago, Ill., a corporation of New York

Application February 24, 1937, Serial No. 67,826

Term of patent 7 years

To all whom it may concern:

Be it known that I, John R. Morgan, a citizen of the Republic of Guatemala, residing at Oak Park, in the county of Cook and State of Illinois, have invented a new, original, and ornamental Design for a Radio Receiver Cabinet, of which the following is a specification, reference being had to the accompanying drawing, forming a part thereof.

Fig. 1 is a perspective view of a radio receiver cabinet embodying my new design.

Fig. 2 is an elevational view of the end of the cabinet not seen in Fig. 1.

The back of the cabinet is plain except for the end grille work partially seen in Fig. 1.

I claim:

The ornamental design for a radio receiver cabinet, as shown and described.

JOHN R. MORGAN.
